UNITED STATES PATENT OFFICE

127,481

DESIGN FOR A TOY LOG LOADING DEVICE

Henry J. Ferri, Port Richmond, Staten Island,
N. Y., assignor to The Lionel Corporation, New
York, N. Y., a corporation of New York

Application March 4, 1941, Serial No. 99,344

Term of patent 14 years

To all whom it may concern:

Be it known that I, Henry J. Ferri, a citizen of the United States of America and a resident of Port Richmond, Staten Island, in the county of Richmond and State of New York, have invented a new, original, and ornamental Design for a Toy Log Loading Device, of which the following is a specification, reference being had to the accompanying drawing, forming a part thereof.

In the drawing:

Figure 1 is a perspective view of the toy log loading device showing my new design; and

Figure 2 is a perspective view of the same from the opposite side.

I claim:

The ornamental design for a toy log loading device, as shown.

HENRY J. FERRI.
